ATTORNEY

UNITED STATES PATENT OFFICE.

JOHN F. LEIDECKER, OF ALAMEDA, CALIFORNIA.

PAPER DISPENSER.

Application filed November 9, 1922. Serial No. 599,795.

My invention is an improved paper dispensing device.

The main difficulty in dispensing rolled paper is that the loose end can not be readily grasped. The roll often turns so that the loose end is at the rear away from the wrapper and it requires considerable time to turn it in the proper position so that a sheet may be torn off.

10 The object of my invention is to provide a dispensing device wherein the end of the paper is always readily accessible.

Other objects are to provide a dispenser which is simple in construction, inexpensive 15 to manufacture and efficient in operation.

In the drawing I have shown one form of my invention, but it may be embodied in other forms and in this specification and appended claims, I wish to cover my invention 20 in whatever form it may be embodied.

Referring to the drawing:

Figure 1 is a side view of my improved paper dispensing device.

25 Figure 2 is a top plan view of the same. Figure 3 is a side view of the same with the side plate removed.

Referring more particularly to the drawing, the numerals 1 and 2 indicate a pair of upright roll supporting posts which are 30 joined at the top by a horizontal bar 3 and secured at their base to a suitable surface. Detachably mounted on the posts 1 and 2 is a paper guide frame 4 which comprises side walls 5 and 6. The walls 5 and 6 are 35 secured to the posts 1 and 2 at their lower end by bolts extending through ears 7 and 8 on the walls 5 and 6 respectively and into the posts 1 and 2. The walls 5 and 6 are secured at their upper end to a horizontal 40 mounting bar 9 which has a groove 10 formed therein for the reception of the bar 3. By this means the frame 4 is securely mounted on the roll supporting posts.

The front wall 11 of the frame 4 has the 45 inner surface inclined slightly inwardly as at 12 to prevent the paper from binding as will be later described. A knife 13 is mounted on the lower edge of the wall 11 against which the paper is torn.

50 A downwardly inclined guide plate 14 is mounted between the sides 5 and 6 and extends from the bar 9 to adjacent the lower edge of the front wall 11, leaving an opening 15 for the passage of the paper.

55 A roller 16 is mounted on a bale 17 near the top and rear of the frame 4. The bale

17 is journaled in the sides 5 and 6 and counter weights 18 and 19 are suspended to said bale below the journals to keep the bale in a normal vertical position. The bale works 60 through slots 20 and 21 in the plate 14.

Vertical guide rods 22 depend from the upper end of the plate 14 and a rider 23 is positioned between them and rests upon the paper roll 24 which is journaled in the uprights 1 and 2. The rider 23 acts as a brake against the paper to prevent it from unwinding any faster than desired.

A tension plate 24 lies on the bar 9 under which the paper is threaded, thence over the roller 16 and down through the opening 15.

As the end of the paper is pulled the tension against the roller 16 causes it to swing forwardly as shown in dotted lines in Figure 3.

The path of the paper through the frame 4 has thus been increased. When the paper

is torn on the knife 13 with the roller in the forward position the tension on the paper is released and the weights 18 and 19 swing the roller 16 to its normal rear position, 75

allowing the paper to lie along the plate 14 which is a shorter distance to the opening 15 than when the roller is swung forwardly and the surplus paper protrudes from the said opening to form a ready hold when a

further supply of paper is required.

The slack producing mechanism and the mechanical method of causing a slack may be adapted to feeding webs of paper or other material, which have an intermittent feed; 80

and may be used in machinery where a slack is necessary as in motion picture cameras and projectors, certain types of bag making machines and so forth. In which case the cutterknife 13 would be omitted, the bar

9 and the opening 15 would function as in and out guide members respectively. The roller 16 does not function as a free rotating roller to allow easy passage of the paper

but has a certain amount of friction on the 95 web to pull the paper when under tension and drawn to the position shown dotted in

Figure 3.

The method of operation is to allow the loose untensioned paper to have a short path 100 between the in and out guides, which may be likened to resting on the base of a triangle 14; and when the web is tensioned and pulled the carrier roller 16 draws the web

105 to follow the upper and vertical sides of the triangle as shown in Figure 3. Thus when the tension is released the roller 16 swings

back to the position adjacent the base 14, the web drops on the base; and the two sides of the triangle being longer than the third the surplus paper projects beyond the out 5 guide 15 as a slack.

Having described my invention, I claim:

1. Dispensing means for a roll of paper revolvably mounted on a horizontal axis comprising a horizontal guide edge spaced 10 from the roll and lying substantially in the horizontal plane of the axis thereof and a yoke pivoted between the guide edge and the roll having weights associated with the free ends thereof so as to normally occupy a 15 vertical position with the base of the yoke presented higher than the roll of paper so as to swing forward with the paper for abnormally increasing the unrolled length thereof when the paper is advanced over the 20 guide edge.

2. Dispensing means for a roll of paper revolvably mounted on a horizontal axis comprising a horizontal guide edge spaced from the roll and lying substantially in the 25 horizontal plane of the axis thereof and a yoke pivoted between the guide edge and the roll having weights associated with the free ends thereof so as to normally occupy a vertical position with the base of the yoke presented higher than the roll of paper and 30 guide means frictionally engaging the paper rearwardly of the base of the yoke.

3. A dispensing device for a revolvably mounted roll of paper comprising a horizontal 35 guide edge mounted in front of the roll and spaced therefrom, and a yoke pivoted between the roll and the guide having its pivot disposed below the roll axis and its base higher than the roll and having means 40 associated therewith for normally holding the same in a vertical position.

4. A vertical frame allowing a roll of paper to be revolvably mounted therein, side 45 walls extending forwardly from the frame, a substantially vertical front wall between the side walls and spaced from the roll, a slanting intermediate wall descending from

the top of the frame toward the lower edge of the front wall so as to form a slot therewith allowing a strip of paper to be guided over the top of the frame and between the intermediate and front walls and through the said slot and means actuated by a pull on the free end of the paper for causing an intermediate portion of the strip to be 50 pressed from the slanting wall toward the front wall whereby the unrolled length thereof is abnormally extended.

5. A vertical frame allowing a roll of paper to be revolvably mounted therein, side 55 walls extending forwardly from the frame, a substantially vertical front wall between the side walls and spaced from the roll, a slanting intermediate wall descending from the top of the frame toward the lower edge 60 of the front wall so as to form a slot therewith allowing a strip of paper to be guided over the top of the frame and between the intermediate and front walls and through the said slot and a yoke pivoted to engage 65 the underside of the paper between the intermediate and front walls so as to be swung forwardly toward the front wall when the paper is pulled on.

6. A vertical frame allowing a roll of 70 paper to be revolvably mounted therein, side walls extending forwardly from the frame, a substantially vertical front wall between the side walls and spaced from the roll, a slanting intermediate wall descending from 75 the top of the frame toward the lower edge of the front wall so as to form a slot therewith allowing a strip of paper to be guided over the top of the frame and between the intermediate and front walls and through 80 the said slot and a yoke pivoted to engage the underside of the paper between the intermediate and front walls so as to be swung forwardly toward the front wall when the paper is pulled on, the said yoke having 85 means for returning the same to an initial position associated therewith.

In testimony whereof I affix my signature.
JOHN F. LEIDECKER.
